CLAIM

The ornamental design for a card file, as shown and described.

DESCRIPTION

FIG. 1 is a perspective view showing my new design for a card file;

FIG. 2 is a right side view of the card file of FIG. 1; the opposite side view being a mirror image thereof;

FIG. 3 is a rear view of the card file of FIG. 1;

FIG. 4 is a front view of the card file of FIG. 1;

FIG. 5 is a top plan view of the card file of FIG. 1; and,

FIG. 6 is a bottom plan view of the card file of FIG. 1.

The dashed lines shown in FIGS. 1–6 illustrate environmental matter and form no part of the claimed design.

1 Claim, 6 Drawing Sheets
